United States Patent Office

Des. 188,401

Patented July 12, 1960

188,401

DISPLAY STAND

Philip G. Lux, 315 W. Franklin St., Elkhart, Ind.

Filed July 1, 1959, Ser. No. 56,611

Term of patent 3½ years

(Cl. D80—9)

FIG. 1.

FIG. 2.

FIG. 3.

Figure 1 is a perspective view of a display stand embodying my new design, the broken line showing being for purposes of illustration only;

Figure 2 is a rear elevational view thereof; and

Figure 3 is a side elevational view thereof.

I claim:

The ornamental design for a display stand, as shown and described.
